DUST GUARD FOR JOURNAL BOXES

Albert O. Buckius, Cleveland, Ohio, assignor to
National Malleable and Steel Castings Company,
Cleveland, Ohio, a corporation of Ohio

Application July 2, 1948, Serial No. 36,674

9 Claims. (Cl. 286--5)

1

This invention relates to a construction for use on a journal box as in a railway car truck, and more particularly, to removably secured means for preventing the entrance of dust, cinders, and moisture into the journal box.

An object of this invention is to provide a detachable housing means involving no wearing parts and effectively preventing the entrance of dust and other foreign materials into a journal box.

Another object of this invention is to provide a detachable means for the elimination of the present dust guard used in conventional journal boxes.

A further object of this invention is to provide a dust deflecting means which is removably secured to a journal box and which is easily and economically manufactured.

A still further object is to provide a dust deflecting housing with a beveled surface for engagement with a corresponding beveled surface on a journal box and adapted to be fastened thereto by a detachable securing member.

Other objects and advantages of this invention will appear in the following description taken in conjunction with the drawings, in which:

Fig. 1 is a longitudinal view partly in section of an embodiment of the invention applied to a journal box;

Fig. 2 is a transverse vertical sectional view taken along line 2--2 of Fig. 1;

Fig. 3 is a transverse vertical view of the embodiment shown in Fig. 2, taken from the wheel side; and

Fig. 4 is a longitudinal sectional view taken along the line 4--4 of Fig. 3.

Referring to the drawings in which like reference numerals indicate like parts, the numeral 10 represents a portion of a conventional journal box containing a wedge 11 and a brass 12 resting on a journal 13. In this embodiment of the invention the journal box 10 does not include the usual dust guard slot, but instead has a single rear wall 29, and a flange 14, with front beveled edge 15 and rear beveled edge 16, which extend around the entire periphery of the journal box to provide means for attaching the dust deflector housing 19. A wheel 17 is mounted on an axle 18 in the usual manner.

The dust deflector housing 19 comprises a portion 20 which is generally conical in shape extending toward the wheel 17 and overlapping the adjacent part of the wheel hub 21. Conical portion 20 terminates in a vertical top flange 22 and a flared flange or bead 23 extending around the two sides and bottom thereof. When the car is

in motion top flange 22 deflects the air stream away from the wheel thus preventing dirt or water from being blown into the opening between the housing and the wheel hub. Flange 22 also serves to prevent water or cinders from falling from the car structure or wheel into the opening at the rear of the journal box while the car is stationary.

Extending radially inwardly from conical portion 20 is flange 24, which conforms to the exterior shape of the journal box 10. Flange 24 has a beveled surface 25 which engages the rear beveled edge 16 of flange 14 around the periphery of the journal box when the dust deflector housing is attached to the journal box.

Extending from flange 24 at the upper end of the housing is a horizontal shoulder 26 having its underside 27 beveled to correspond in slope with front beveled surface 15 of flange 24. It will be seen that beveled surface 25 on flange 24 and beveled surface 27 on shoulder 26 form an inverted V-shaped groove which receives flange 14, thus providing means for fastening the dust deflector housing to the journal box. Also at the bottom of opening 30 the housing is provided with a depending flange 28 having a lug 31 which projects outwardly to the front of, and extends along the entire base of, flange 28.

A securing plate 32 is provided for locking the housing to the journal box. This plate is formed with pads 33 which are beveled as shown at 33 to engage front beveled edge 15 of flange 14, and also has pads 34 on its underside which bear against the upper surface 37 of lug 31. Plate 32 is clamped to flange 28 by any suitable fastening means such as rivets 35. As the plate is secured in place the wedging action of surface 25 of the housing and surface 33 of the plate against flange 14 along the bottom of the journal box force the flange 14 at the top of the journal box into engagement with the aforementioned groove formed by surfaces 25 and 27. Also this wedging action urges beveled surface 25 into engagement with rear beveled edge 16 of flange 14 around the entire periphery of the journal box. In this manner the dust deflector housing is securely attached to the journal box and makes surface contact with the end thereof about its entire periphery.

The detachable dust deflector housing can be readily applied or removed, is easily produced, and economically manufactured. Also, it forms an efficient means for preventing the entrance of dust and other foreign materials into the box, without the use of wearing parts.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. A journal box, a journal extending into said box, a wheel on said journal having a hub portion adjacent the end of said box, said box having a flange extending about the periphery thereof and being positioned adjacent said wheel hub, a housing member overlapping and surrounding said wheel hub and engaging said flange, said member having a horizontal top portion forming a recess for receiving said flange for supporting said member on said box, said housing member having a depending flange on the other side thereof, and a removable member for securing said housing member to said box, said removable member engaging the forward side of said flange on said box and being secured to said depending flange.

2. A journal box, a journal extending into said box, a wheel on said journal having a hub portion adjacent the end of said box, said box having a beveled flange about the periphery thereof and being positioned adjacent said wheel hub, a housing member overlapping and surrounding said wheel hub, said housing member having a beveled surface about its entire periphery and engaging said flange, a horizontally extending shoulder at the upper end of said housing member forming with said beveled surface, a groove for receiving said beveled flange for supporting said housing member, and a removable member for securing said housing member to said box, said removable member engaging the forward side of said beveled flange and being secured to said housing member.

3. In combination with a journal box having a flange extending therearound at the rearward end thereof, a housing member attached to the rearward end of said box and overlapping the hub of an associated wheel, said flange having a forward beveled surface and a rearward beveled surface, said housing member having a beveled surface for engagement with said rearward beveled surface on said flange, a horizontally extending shoulder at the upper end of said housing for wedging engagement with said forward beveled surface, and a detachable member fastened to said housing for securing said housing member to said box, said detachable member having wedging engagement with the lower portion of said forward beveled surface to urge said housing member against said box along said beveled surface of said housing member.

4. A journal box, a journal extending into said box, a wheel on said journal having a hub portion adjacent the end of said box, said box having a flange about the periphery thereof and being positioned adjacent said wheel hub, said flange being beveled on both front and rear sides, a housing member overlapping and surrounding said wheel hub, an outwardly extending shoulder at the upper end of said housing member, said housing member having a beveled surface engaging said beveled rear side of said flange, said shoulder having a beveled surface on the under side thereof for engaging said beveled front side of said flange to support said housing member on said box, and a removable member for urging

said beveled surface on said housing member tightly against said beveled rear side of said flange, said removable member engaging said beveled forward side of said flange and being secured to said housing member.

5. A journal box having a flange extending therearound and positioned at the rearward end thereof, said flange being beveled on both front and rear sides, a housing member overlapping and surrounding an associated wheel hub, said housing member having a beveled surface engaging said beveled rear side of said flange and having an outwardly extending shoulder at the upper end thereof, said shoulder having a beveled surface on the under side thereof for engaging said beveled front side of said flange, a removable member having an upper beveled surface for wedging engagement with the lower portion of the front beveled side of said flange to urge said beveled surface on said housing member into tight contact with said beveled rear surface of said flange, said removable member being secured to said housing member.

6. A journal box having a peripheral flange at the rear portion thereof, said flange being beveled on both front and rear sides, a housing member adapted to be secured to the end of said box for overlapping and surrounding an associated wheel hub, said housing member having a beveled peripheral surface engaging the rear side of said flange and having an outwardly extending shoulder at the upper end thereof for supporting said housing member on said box, said shoulder having a beveled surface on the under side thereof for engaging the front beveled side of said flange, said housing having a flange depending from the lower end thereof, and a member fastened to said last named flange to secure said housing member to said box, said last named member engaging the front beveled surface of said flange on said box, and wedging said beveled peripheral surface on said housing member against said rear side of said flange on said box.

7. A dust deflector housing having an opening for receiving the end of a railway journal box, said housing having a beveled surface about said opening for engagement with a similar beveled surface on a peripheral flange of an associated journal box, an outwardly extending shoulder at the top thereof, and a flange depending from the bottom thereof, said shoulder having a beveled surface on the under side thereof to form a groove with said beveled surface on said housing, said groove being adapted to receive said flange on the associated journal box, said flange of said housing having a forwardly extending lug at the bottom thereof and a detachable member having a beveled top surface for engaging said flange on the associated journal box, said detachable member bearing against said lug and being fastened to said flange of said housing for securing said housing to the associated journal box.

8. A journal box having a beveled flange extending therearound and positioned at the rearward end thereof, a dust deflector housing having an opening for receiving the end of said box, said housing having a beveled surface about said opening for engaging said flange, said housing having a shoulder at the top thereof for engaging said flange for supporting said housing on said box, said housing having a flange depending from the bottom thereof, and a removable member having a beveled top surface engaging said first mentioned flange, said removable member being fastened to said second mentioned

flange for securing said housing to said journal box.

9. A dust deflector housing having an opening for receiving the end of a railway journal box, said housing having a beveled surface extending entirely about said opening for engagement with a similar beveled surface on a peripheral flange of an associated journal box, said housing having at its upper end a surface positioned at an angle to said beveled surface for supporting said housing on said flange of an associated box, a flange depending from the bottom of said housing, and a member detachably fastened to said depending flange for securing said housing to said box, said member having a wedge shaped surface for engagement with said flange of an associated journal box to urge said housing into tight en-

gagement with said box along said beveled surface of said housing.
